Fig. 4.

To all whom it may concern:

Be it known that I, Jean O. Reinecke, a citizen of the United States, residing at Oak Park, in the county of Cook and State of Illinois, have invented a new, original, and ornamental Design for a Unit Heater, of which the following is a specification, reference being had to the accompanying drawings, forming part thereof.

In the drawings:

Fig. 1 is a side elevational view of a unit heater embodying my new design;

Fig. 2 is a top plan view of the same;

Fig. 3 is a perspective view taken from the bottom and one side; and

Fig. 4 is a frequently side elevation partly in section of the unit heater.

I claim:

The ornamental design for a unit heater, as shown.
